UNITED STATES PATENT OFFICE

RAYMOND L. McBETH, OF FRUITA, COLORADO

CLOTHES BASKET CARRIER

Application filed May 13, 1931. Serial No. 537,169.

This invention relates to an improved clothes basket transporting device in the nature of a mobile carrier adapted to be used in association with a track forming wire.

5 In accordance with the present invention I provide an extra suspension wire which may be ordinary clothesline wire, the same being adapted for disposition between spaced parallel clotheslines, and designed to accommodate 10 an especially constructed carrier fashioned to accommodate a clothes containing basket, whereby to permit the user to move the basket from place to place along the track to facilitate hanging and gathering 15 of clothes, and to provide a means for convenient access to a clothespin bag such as may be attached to the carrier.

More explicitly stated, the invention is embodied in a specially designed carrier characterized by a suitable horizontal platform, an overhead pulley equipped trolley, and suspension links carried by and depending from said trolley, and detachably connected at their lower ends with the platform.

25 In the drawings:

Figure 1 is an end elevational view of a structure designed in accordance with the present invention.

Figure 2 is a side view with portions shown 30 in section.

Figure 3 is a plan view of the platform, the section being on the line 3-3 of Figure 2.

Figure 4 is a fragmentary perspective view 35 of one corner portion of the platform.

Figure 5 is a view showing the link connection with the platform.

Figure 6 is a perspective view of one of the suspension links.

Figure 7 is a detail section through the 40 sheave and rail assembly.

In Figure 2 of the drawings, it will be observed that the track forming wire or trolley line is designated by the numeral 8 and is adapted to accommodate a part 9 which may be generally referred to as a trolley unit. This comprises a pair of longitudinal spaced parallel rails 10 having a pair of longitudinally spaced pulley assemblies at opposite ends.

50 In Figure 7 for example, each assembly

comprises a pulley guard 11 interposed between the adjacent ends of the rails 10 and held therebetween by a connecting pin 12. This pin 12 constitutes an axle for the sheave or pulley 13, said sheave being designed to travel along the trolley line 8.

The casting forming the pulley guard 11 is provided with an integral pendant 14 apertured to form a suspension eye. The aforesaid platform is denoted by the numeral 16 and this comprises a pair of horizontal spaced parallel side bars 17 joined together by transversely disposed longitudinally spaced slats 18.

The end portions of the bars 17 are extended and apertured as at 19 to form keeper holes. The platform is detachably connected with duplicate suspension means. The means at each end is the same and a description of one will suffice for both. Said means 60 comprises a pair of like rods or links 20 having hooks 21 at their lower ends detachably connected with the holes 19 as shown better in Figure 5.

These rods are formed with eyes 22 at the 65 upper ends swingably mounted in an elongated loop 23 forming a part of a coupling bracket 24. This bracket also includes a hook 25 detachably engageable with the eye 14. Incidentally, the clothes basket is designated 70 by the numeral 26.

In practice, the clothes basket is placed on this platform 16 as shown in dotted lines in the drawings so that a carrier may be adjusted back and forth on the trolley line to 85 permit expeditious selection and hanging of clothes on a supplemental line (not shown); or gathering of the clothes and replacement in the basket. The platform being detachable from the suspension links 21 may be employed 90 as a convenient rack, if desired, in carrying the basket to and from the house.

The gist of the invention, it will be seen, is in the provision of a simple and economical trolley or track forming wire suitably suspended at a point between a pair of clothes lines, together with a duplex trolley unit adjustable along said line, said unit being constructed to accommodate the duplicate hangers or suspension devices, and said suspen- 100

sion devices serving to accommodate the detachable slotted platform.

It is thought that the description taken in connection with the drawings will enable 5 a clear understanding of the invention to be had. Therefore, a more lengthy description is thought unnecessary. While the preferred embodiment of the invention has been shown and described, it is to be understood that 10 minor changes coming within the field of invention claimed may be resorted to if desired.

I claim:

In a clothes carrier of the type described, 15 a pair of bars, pulley guards arranged closely between the end portions of the bars and maintaining the same in spaced parallel relation, pins passing through the bars and the guards to secure the guards between the bars, pulleys mounted on said pins within said 20 guards, couplings detachably suspended from said guards, pairs or diverging links depending from said coupling, and a platform having the corners thereof engaged by said links.

In testimony whereof I affix my signature.
25 RAYMOND L. McBETH.
